UNITED STATES PATENT OFFICE.

LYDIA J. CADWELL, OF CHICAGO, ILLINOIS, ASSIGNOR TO THE METAL BLOCK PAVEMENT COMPANY, OF ILLINOIS.

PAVEMENT.

SPECIFICATION forming part of Letters Patent No. 398,940, dated March 5, 1889.

Application filed July 9, 1888. Serial No. 279,354. (No specimens.)

To all whom it may concern:

Be it known that I, LYDIA J. CADWELL, of Chicago, in the county of Cook and State of Illinois, have invented certain new and useful 5 Improvements in Pavements; and I do hereby declare that the following is a full, clear, and exact description thereof, reference being had to the accompanying drawings, and to the letters of reference marked thereon, which 10 form a part of this specification.

The invention herein set forth is intended as an improvement in pavements of that class which are composed of T-shaped blocks placed alternately in inverse positions, so as to overlap each other in the finished pavement for the more extended distribution over the bed of the weight to which the pavement is subjected, an example of such pavement being set forth in a prior application for patent filed 15 by me—to wit, Serial No. 260,607. In said prior application the blocks composing the pavement are of the same general shape herein shown; but the meeting end faces of the longer and shorter parts are substantially 20 vertical, or so inclined as to permit any one of the blocks to be lifted out of its place in the pavement. In the present improvement the blocks are constructed to interlock against 25 vertical displacement.

30 Referring to the accompanying drawings for an illustration of my invention, Figure 1 is a top view of a pavement composed of my improved block, in which the blocks are laid end to end and with their edges in line. Fig. 35 2 is a top view of the pavement, in which each end of each block partially overlaps two neighboring blocks and covers the seam between the latter. Fig. 3 is a side view of one of the blocks detached from the pavement. 40 Fig. 4 is a side view of a series of blocks in their relative position in the pavement, and showing in what manner they interlock against vertical displacement. Fig. 5 is a transverse vertical section of the block in the line 5 5 of Fig. 3. Fig. 6 is a transverse vertical section in the line 6 6 of Fig. 3. Fig. 7 is a perspective of a fragment of a block, showing more clearly the form of the ribs shown in Figs. 1 and 2. Fig. 8 is a vertical longitudinal section of a block having internal 45 50 grooves opposite the external ribs.

A represents a single block of broad T shape, having two parallel long and short faces, a a' , the latter being centrally opposite the former. Both end surfaces of the block 55 are similar and are composed severally of the three intersecting surfaces a^2 a^3 a^4 , of which a^2 and a^4 are substantially parallel to each other and inclined to the planes of the top and bottom surfaces, a a' , so as to present the 60 salient angle or projection at a^5 and the re-entering angle or recess at a^6 . These angles are at substantially equal distances from the planes of the surfaces a a' , so that the projection a^5 of one block enters the re-entering 65 angle or recess a^6 of an adjacent block when placed together in the proposed order, as shown in Fig. 4. Thus constructed and joined it is manifest that the blocks cannot be separately lifted out of place, and that the pavement, as a whole, is better calculated to 70 preserve an even surface. The intermediate end surface, a^3 , may be either parallel with the top and bottom faces, a a' , or acutely inclined thereto, as shown.

In Figs. 1 and 2 of the drawings the blocks are shown arranged with their greater length running with the street and the blocks as having their foot-hold ribs a^7 and intermediate grooves transverse. While ribs and 80 grooves of any description and arrangement may be employed, I have shown as a particular improvement an arrangement seen in Fig. 7. Here the ribs a^7 stop short of one edge of the block and the spaces between said ribs 85 are closed at one point by a traversing or lengthwise rib, a^8 . This gives holds for the shoe-calks of horses in both directions of travel, and in the case of cast or molded blocks permits the blocks or the pattern from 90 which the blocks are cast to be drawn sideways from the mold.

In Fig. 8 the interior surfaces of the ribbed walls are corrugated by grooves a^9 opposite the ribs, which construction lightens the block 95 and at the same time strengthens it. The grooves are indicated by dotted lines in Figs. 1 and 2, where is also shown a practical distribution of vertical struts a^{10} , which support the upper from the lower surface of the block 100 when the latter is in use.

The walls a and a' of the block may be per-

forated, if desired, as shown at the lower right hand in Fig. 2.

It is contemplated that the blocks A will be made hollow, as shown, and filled with sand and asphalt, or some other suitable material, to prevent resonance and add strength, as set forth in my said prior application. The walls of the blocks may, I have found, be made relatively thin by supplying struts at short intervals, as shown, and particularly by adding a compact filling in re-enforcement of such struts.

I claim as my invention—

1. A pavement composed of substantially T-shaped blocks having their contiguous end faces overlapped and also interlocked against vertical displacement when laid, substantially as described.
2. A pavement composed of overlapping

blocks severally provided with a long face on one side, a short centrally-opposite parallel face on the opposite side, and end faces provided with mutually-engaging projections and recesses, substantially as described, and for the purposes set forth.

3. A pavement composed of overlapping blocks severally provided on their opposite parallel faces with transverse ribs terminating at one end short of the edge of the block and having a longitudinal rib which intersects the transverse ribs, substantially as described.

In testimony that I claim the foregoing as my invention I affix my signature in presence of two witnesses.

LYDIA J. CADWELL.
